CLAIM

The ornamental design for a hose holder, as shown and described.

DESCRIPTION

FIG. 1 is a top front perspective view of a hose holder showing my new design;

FIG. 2 is a bottom front perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a left side elevational view thereof, showing the plane upon which a cross-sectional view is taken and shown in FIG. 10; and,

FIG. 10 is an enlarged, cross-sectional view taken along line 10-10 in FIG. 9.

1 Claim, 10 Drawing Sheets
